UNITED STATES PATENT OFFICE.

JAMES C. BROWN, OF SEDALIA, MISSOURI.

MAIL-BAG LOCK.

SPECIFICATION forming part of Letters Patent No. 380,986, dated April 10, 1888.

Application filed September 9, 1887. Serial No. 249,258. (No model.)

To all whom it may concern:

Be it known that I, JAMES C. BROWN, a citizen of the United States, residing at Sedalia, in the county of Pettis and State of Missouri, have 5 invented new and useful Improvements in Mail-Bag Locks, of which the following is a specification.

My invention relates to that class of mail-bag locks in which the lock-case is formed with 10 a hasp to engage a staple on the mail pouch or bag and partly inclose a pair of pivoted locking-arms having curved ends adapted to pass through said staple from opposite sides.

The invention consists in a novel mechanism 15 for actuating the pivoted spring locking-arms of a hasp-lock, and in the construction and combination of parts, hereinafter described and claimed.

In the annexed drawings, illustrating the invention, Figure 1 is a perspective view of my 20 improved mail-lock. Fig. 2 is a plan view of the same with the front plate removed, showing the spring locking-arms engaged with staple and locked by bolt. Fig. 3 is a similar 25 view showing the spring-arms unlocked. Figs. 4, 5, and 6 are detail views.

The lock-case 1 is formed with a back plate, 2, having at one end an aperture, 3, for the 30 passage of a ring, staple, or other fastening, 4, by which the lock can be attached to a mail bag or pouch, 5, in any convenient manner. At its other end the back plate, 2, is shaped to form a hasp, 6, for engaging a staple, 7, on the mail-bag.

One end of the lock-case is provided with 35 openings 8, through which project the curved ends of a pair of locking-arms, 9, that are pivoted to the back plate, 2, within the lock-case. The outer ends of these locking-arms are so formed as to meet and interlock across the hasp-slot, as shown in Fig. 2, so that when the hasp 6 is passed over the staple 7 the curved 40 ends of the locking-arms 9 can be engaged through or in the staple, and thereby secure the mouth of the mail-bag. Between the pivoted locking-arms 9 is arranged a spring, 10, which acts to throw the curved ends of said locking-arms outward, as shown in Fig. 3, thereby disengaging them from the staple 7 45 so when a bolt, 11, is withdrawn from between the rear or inner ends of said arms.

The bolt 11 is adapted to slide forward and back between guide-blocks 12, 13, and 14, arranged in the lock-case, and is drawn from its engagement with the pivoted arms 9 by means of a key, 15, of the ordinary construction employed in mail-locks. The bolt 11 has at its forward or acting end a lug, 16, to enter between the inner or rear ends of the pivoted arms 9, thereby holding the curved ends of said 55 arms firmly together in such close contact that they cannot be separated or disengaged from the staple 7 without first drawing the bolt.

At the rear end the bolt 11 is bifurcated or provided with a recess, 17, to receive a spiral 60 spring, 18, by which it is forced into engagement with the locking-arms, and at this end it also has a lug, 19, forming a bearing for one end of the spring 18, the other end of which is mounted on a guide-pin, 20, projecting inward 65 from one end of the lock-case.

The center of the bolt 11 is provided with a slot, 21, bridged by wards 22, to engage corresponding clefts between the wards 23 of the key. 75

The key-barrel is made to fit a key spindle or pivot, 24, that projects from one side of the lock-case across the bolt 11 and enters the key-hole 25, which is formed partly in the guide-block 14 and partly in the side of the lock-case 80 adjacent to said guide-block.

One side of the bolt 11 is formed with a notch or recess, 26, to receive a lug or detent, 27, carried by a collar, 28, which is mounted loosely on the spindle 24, and is forced toward the bolt 85 by a spiral spring, 29, located on the spindle between said collar and the lock-case. When the bolt 11 is thrown forward by the spring 18, the bolt-lug 16 will be between the rear ends of the pivoted arms 9, thus locking together 90 the forward or curved ends of said arms, the spring 29 at the same time forcing the collar 28 along the spindle 24 until the lug or detent 27 engages the notch or recess 26 in the side of the bolt. It will thus be seen that the bolt 95 cannot be withdrawn except by a key adapted to first force the sliding collar 28 and attached lug 27 back between the guide-blocks 12 and 13, after which the key can be turned, with its wards 23 engaged between the wards 22 of the bolt, so that the pressure of the key-wards 100 against the rear end of the slot 21 will carry

the bolt backward against the force of the spring 18 at its rear end.

As soon as the bolt is withdrawn the tension of the spring 10 between the pivoted locking-arms 9 will force the forward ends of said arms apart and enable the hasp to be disengaged from the staple.

In applying the lock it is only necessary to pass the hasp over the staple and then press 10 the outer or curved ends of the arms together by means of thumb-pieces 30, mounted thereon. It will be seen that as the outer ends of these pivoted arms 9 are thus made to approach each other through the staple their 15 inner ends are separated to receive the bolt 11, which is immediately projected forward by the tension of the springs at its rear end.

The construction of this lock is such that it can be manufactured at comparatively small 20 cost, while the simplicity and durability of the parts obviate the ordinary liability of disarrangement and greatly reduce the expense of repairs. It also affords a secure and reliable fastening that can be used with the keys usually employed in mail-bag locks.

If desired, the front plate of the lock-case can be made with a shallow open-front chamber, 31, for receiving a destination tag.

What I claim as my invention is—

1. In a mail-bag lock, the combination, with 30 a lock-case formed with a hasp, of a pair of locking-arms pivoted in said case and having curved ends adapted to pass through a staple engaged in said hasp, a spring located between said pivoted arms to throw their curved 35 ends apart, and a sliding bolt adapted to enter between the rear or inner ends of said arms and thereby hold their opposite curved ends firmly together, substantially as described.

2. The combination of a lock-case formed 40 with a hasp, a pair of locking-arms pivoted in said case and adapted to interlock at one end across the hasp slot, a spring located between said arms to throw their interlocking ends apart, a sliding bolt adapted to enter between 45 the inner ends of said arms and thereby hold their interlocked ends together, and a spring-actuated collar mounted on the key-spindle and having a lug to engage a notch in the sliding bolt, substantially as described.

In testimony whereof I affix my signature in presence of two witnesses.

JAMES C. BROWN.
